(57) **CLAIM**

The ornamental design for a laptop computer lap desk, as shown and described.

DESCRIPTION

FIG. 1 is a top view of a laptop computer lap desk showing my new design.

FIG. 2 is a bottom view of the laptop computer lap desk.

FIG. 3 is a side view of the laptop computer lap desk.

FIG. 4 is a back view of the laptop computer lap desk.

FIG. 5 is a front view of the laptop computer lap desk; and, FIG. 6 is a perspective view of the laptop computer lap desk.

The broken lines are for illustrative purposes only and form no part of the claimed design.
